UNITED STATES PATENT OFFICE.

SOLOMON M. CUTTER, OF ASHLAND, MASSACHUSETTS, ASSIGNOR TO UNITED SHOE MACHINERY COMPANY, OF PATERSON, NEW JERSEY, AND BOSTON, MASSACHUSETTS, A CORPORATION OF NEW JERSEY.

NAILING-MACHINE.

No. 886,313.

Specification of Letters Patent.

Patented April 28, 1908.

Original application filed April 19, 1898, Serial No. 678,148. Divided and this application filed December 16, 1901. Serial No. 86,083.

To all whom it may concern:

Be it known that I, SOLOMON M. CUTTER, a citizen of the United States, residing at Ashland, in the county of Middlesex and 5 Commonwealth of Massachusetts, have invented an Improvement in Nailing - Machines, of which the following description, in connection with the accompanying drawings, is a specification, like letters on the drawings 10 representing like parts.

This invention relates to nailing machines and particularly to nailing machines used in the manufacture of boots and shoes.

An object of the invention is to improve 15 and simplify the construction of such machines, especially with respect to the arrangement and timing of the nail-delivering and nail-inserting mechanisms.

In the accompanying drawings,—Figure 1 20 is a side view of part of a nailing machine embodying my invention. Fig. 2 is a front elevation of the part of the machine shown in Fig. 1. Fig. 3 is a front view partially in section of the carrier for placing the 25 nail in position to be driven. Fig. 4 is a detail showing the wire cutter and part of a lever for moving it. Fig. 5 is a horizontal section on line y , Fig. 6, through the wire feeding mechanism, said figure showing the 30 wire cutter occupying a position parallel with the longitudinal axis of the carrier, and Fig. 6 is a vertical section parallel with the driver bar, and through the wire feeding mechanism, the line of section being transverse to the 35 longitudinal axis of the carrier.

The head a of the machine erected on a suitable column a' has suitable bearings to sustain the driving shaft a^2 provided at one end with a cam a^3 having operating parts a^4 , 40 a^5 , and carrying a crank pin a^6 . The crank pin a^6 carries a link b jointed at its lower end to a driver bar b^x free to be reciprocated in the head a and provided with a driver b^2 . The part a^4 of the cam a^3 moves a lever b^3 pivoted 45 at b^4 and employed to move a bar b^5 carrying an awl b^6 laterally in a direction to enable the awl forced into the stock to feed the stock in usual manner toward the driver and between a stock support 2 and a foot plate 3 of any 50 usual construction. A spring c attached at

one end to the lever b^3 , and at its other end to the frame, tends to maintain the roll c' of the lever b^3 in contact with the operating part a^4 of the cam a^3 . A spring c^2 attached to the awl bar and to the frame moves said bar 55 away from the driver as the lower end of the lever b^3 is moved away from the driver.

The awl carrying bar b^5 is pivoted to the free end of a lever c^3 mounted on a shaft c^4 said lever having an arm c^5 provided with a 60 roller stud c^6 that enters a cam d at the rear side of the cam a^3 , said groove actuating the lever c^3 to reciprocate the awl bar positively in both directions, that the awl may penetrate the stock and be withdrawn therefrom 65 after the operation of feeding the stock.

The parts so far described are substantially the same as described in United States Letters Patent No. 582,579, dated May 11, 1897. 70

The head has a pivot d' for a lever d^2 actuated by the operating part a^5 of the cam a^3 , the lever reciprocating the wire cutter d^8 to be described. The continuous wire e from which the nails are to be cut, is supplied 75 by any suitable reel as A, and is led therefrom through a wire guide e' where it is acted upon by a suitable wire feeding mechanism shown as a toothed wheel e^2 mounted on a shaft e^4 provided at one end with a ratchet 80 wheel e^5 , see Fig. 1, that is engaged and rotated intermittently by a suitable pawl e^x at the end of a lever e^6 provided at its upper end with screws e^7 , e^8 , the adjustment of which determines the extent of 85 movement of the lever e^6 , and consequently the distance that the wire is fed at each operation of the feeding device. The screw e^8 engages the head a and limits the forward movement of the upper end of the lever e^6 , 90 while the screw e^7 is maintained against one end of a sliding pin 5 having a cam roll 6 that is acted upon by the cam surface 7 at the rear of the cam a^3 . The sliding pin is restrained from rotation by means of a pin 95 10 entering a groove in the side thereof. A spring 8 connected with lever e^6 acts normally to hold the screw e^7 against the inner end of the sliding pin. The wire is held 100 pressed against the periphery of the feed

wheel e^2 by a roll f mounted on a stud f^x carried by a lever f' pivoted at f^2 and held yieldingly by a spring f^3 controlled by a screw f^4 . The feed wheel moves the wire 5 longitudinally so that its free end enters a passage in a nail carrier g represented as an enlarged circular block at one end of a rock shaft g' having its bearing between a support shown as two plates g^2, g^3 , concaved 10 and held together by a suitable screw as g^4 and presenting between them immediately above and below the carrier a driver passage g^x .

The shaft g' has secured to it an arm g^5 shown as provided with a cam groove g^6x 15 that is entered by a stud 12 see Fig. 3 on a movable throat piece 13 having a passage 14 to receive the nail acted upon by the driver as the same leaves the carrier, said throat directing the nail while it is being driven into 20 the stock, the cam groove causing the throat to be moved longitudinally to occupy a position to place its passage in the line of the driver when a nail is to be driven, and moving the throat away from the path of the driver 25 when the awl is acting to feed the stock, the driver being then elevated. The arm g^5 has a connected link g^6 that is jointed to a lever g^7 having a roller stud that enters a cam groove g^8 in a block g^9 fast on shaft a^2 .

30 The wire cutter d^8 is located in a space 15 between the inner plate g^3 and the head of the machine, and it has a recess 16, see Figs. 4 and 5, at one side to receive the lower end 35 of the lever d^2 referred to, which is actuated by the part a^5 of the cam a^3 . The cutter d^8 is moved in a line parallel with the longitudinal axis of the shaft g' , and meets the wire at right angles to its longitudinal axis at a point close to the face of the carrier, and the wire is 40 cut off in nail lengths and left in the carrier so that when a circular movement is given to the shaft g' and carrier the nail is turned from a horizontal into a vertical position, and is put under the line of movement of the 45 driver, and the plate g^2 prevents the escape of the nail until it arrives opposite the passage g^x .

The head of the machine has connected 50 with it by a screw 17 a stationary cutter 18, see Figs. 4 and 6, which in case the cutter d^8 fails to act, meets the wire as the carrier is moved circularly, and cuts off the wire leaving a nail in the carrier. This cutter also 55 meets the wire substantially at right angles to its longitudinal axis, and if one cutter fails the other is sure to act and prevent any breaking of the parts. The stationary cutter 18 is entirely independent of the movable cutter d^8 , each performing its severing operation 60 at different times and without the aid of the other. One means of securing this independence of action is by arranging the cutter 18 in such a position relative to the carrier g that its cutting edge is at all times

in a different plane from the cutting edge of 65 cutter d^8 from which it follows that the two cutting edges can never co-act to perform a severance of the wire.

Fig. 6 shows a spring 19 connected with the head and bearing at its free end on the 70 wire to aid in directing it into the passage in the carrier.

Having described my invention, what I claim and desire to secure by Letters Patent is:—

75 1. In a nailing machine, a circularly movable carrier having a passage to receive wire, a bar having a knife edge at one end in contact with the carrier, means to reciprocate said knife edge across the passage in the carrier to sever the wire, and means for preventing the severed nail from dropping out of the carrier.

80 2. In a nailing machine, a cylindrical carrier having a passage to receive wire, a wire cutter in contact with said carrier, means to move said cutter in a direction parallel to the longitudinal axis of the carrier and across said passage to sever the wire, means to thereafter partially rotate said carrier to bring its passage into driving position, and means for preventing the severed nail from dropping out of the carrier.

85 3. In a nailing machine, a cylindrical nail carrier having a passage to receive wire, a support for said carrier providing a driving passage extending on opposite sides thereof, a cutter in contact with the carrier, means to move the cutter longitudinally of the axis of the carrier and across one end of said passage 90 to sever the wire, and means to thereafter partially rotate said carrier to bring its passage into alignment with the driver passage.

95 4. In a nailing machine, a driver, a cylindrical nail carrier having a passage to receive the end of a wire, a cutter movable longitudinally of the axis of the nail carrier to sever the wire into nail lengths, means to thereafter partially rotate said carrier in one direction to place the nail in line with the 105 driver and to then return said carrier into nail receiving position, a stationary wire cutter in contact with said carrier and having a cutting edge at right angles to the cutting edge of the movable cutter, said stationary 110 cutter severing the wire during the rotative movement of the carrier in case the movable cutter fails to completely sever it.

115 5. In a nailing machine, a cylindrical nail carrier having a nail passage at right angles to its longitudinal axis, means to oscillate said carrier about its longitudinal axis, means to feed a wire into said nail passage, a plate to close one end of said passage when the wire is inserted therein, a driver passage 120 formed in said plate, a driver, a wire cutter, and means to move said cutter to sever the 125 wire.

6. In a nailing machine, a carrier comprising a rock-shaft having a circular block to receive the end of the wire, a movable cutter, means to actuate the same parallel with the longitudinal axis of said rock-shaft to cut the wire while the carrier is stationary, means to partially rotate said carrier, and a stationary cutter which in case the movable cutter fails to cut the wire will do so after the 10 circular movement of the carrier has been started.
7. In a nailing machine, a circularly moving carrier having a passage to receive the end of a wire, a support having a driver passage and adapted to sustain said carrier, means to turn said carrier in said support, a movable nail-throat co-acting with said support and occupying a position to close the driver passage when the end of the wire is inserted in the passage of the wire carrier, and means to turn said carrier and move said throat to place the hole in the throat in line with the driver passage in said support and in line with the passage in the nail carrier.
- 25 8. In a nailing machine, a carrier adapted to receive the end of a wire, means to move said carrier circularly, a nail throat, and means intermediate said carrier and throat whereby the latter has imparted to it a reciprocating motion while the carrier is being turned to and fro.
9. In a machine of the class described, two plates, a rock shaft provided at its end with a nail carrier having its bearings in and between said plates, one of said plates having a groove at its rear side, a cutter located in said groove, a lever to move said cutter at right angles to the longitudinal axis of the wire, and means to partially turn said rock shaft to place a nail therein in driving position.
- 40 10. In a machine of the class described, two plates, a rock shaft provided at its end with a nail carrier and having its bearings in and between said plates, one of said plates having a groove at its rear side, a cutter located in said groove, a lever to move said cutter at right angles to the longitudinal axis of the wire, means to partially turn said rock shaft to place a nail therein in driving position, a nail throat and means to move it to place the passage therein in line with and then out of line with the path of the driver, and an awl to feed the stock.
- 45 55 11. In a nailing machine, a carrier having a passage to receive the end of the nail, plates embracing said carrier and having between them a vertical passage for the action of the driver, a cutter to sever the wire and leave a nail in said passage, and means to partially turn said carrier and place the passage therein containing the nail in line with the driver passage, one of said plates preventing the es- cape of the nail while the carrier is being turned from its nail receiving position into the position from which the nail is driven therefrom.
- 5 12. In a nailing machine, a carrier constructed to receive a nail, means to move said carrier and its contained nail into nail-driving position, and a movable nail-throat acting in conjunction with and controlled by the movement of said carrier.
- 15 13. In a nailing machine, a cylindrical carrier constructed to receive a nail, means for rotating said carrier from nail-receiving to nail-driving position, and a movable nail-throat controlled as to its movement by the rotation of said carrier.
- 20 14. In a nailing machine, a carrier having a passage to receive the end of a wire, a movable cutter, means to actuate said cutter and a stationary cutter, said cutters being arranged with their cutting edges in contact with said carrier, but at different points, and means to move said carrier whereby if one cutter fails to sever the wire the other will act to sever the wire.
- 25 15. In a nailing machine, a carrier having a passage to receive the end of a wire, a cutter constructed and arranged to move in contact with the carrier and across the end of said passage to sever the wire, means to thereafter move said carrier into driving position, and an auxiliary stationary cutter acting during the movement of the carrier and independently of said movable cutter to sever the wire in case the movable cutter fails to act.
- 30 35 16. In a nailing machine, a carrier having a passage to receive the end of a wire, a cutter constructed and arranged to move in contact with the carrier and across the end of said passage to sever the wire, means to thereafter move said carrier into driving position, and an auxiliary stationary cutter acting during the movement of the carrier and independently of said movable cutter to sever the wire in case the movable cutter fails to act, said stationary cutter being also in contact with the carrier but arranged with its cutting edge at all times in a different plane from the cutting edge of the movable cutter.
- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900

and out of the path of the awl during the work-feeding movement of the latter, and means connected to said nail throat to move in timed relation therewith for delivering a nail to said throat as it again comes into line beneath the driver.

In testimony whereof, I have signed my

name to this specification, in the presence of two subscribing witnesses.

SOLOMON M. CUTTER.
